DESIGN FOR A SINKER FOR FISHING LINES

George W. Moitoza, San Francisco, Calif.

Application February 20, 1936, Serial No. 61,273

Term of patent 3½ years

To all whom it may concern:

Be it known that I, George W. Moitoza, a citizen of the United States, residing in the city and county of San Francisco and State of California, have invented a new, original, and ornamental Design for a Sinker for Fishing Lines, of which the following is a specification, reference being had to the accompanying drawing, forming a part thereof.

In the accompanying drawing:

Fig. 1 is a perspective of a sinker for fishing lines showing my design;

Fig. 2 is an end view of the same; and

Fig. 3 is a side view of the same.

I claim:

The ornamental design for a sinker for fishing lines as shown.

GEORGE W. MOITOZA.
